Claims priority, application Germany June 30, 1955

3 Claims. (Cl. 179—17)

This invention relates to a party line telephone switching system and is particularly concerned with connector switches having two directions of motion for selectively extending calls to party line subscribers.

Each party line is connected to the connectors only once regardless of the number of subscribers connected thereto. The selection of the ringing current provided for a desired party line subscriber or of the corresponding code signal combination may be effected by a ring control switch cooperating with the connector, and such ring control switch may be set by a special impulse series. The party line subscribers may be subdivided into two groups in order to avoid, in the case of a relatively great number of subscribers on a party line, for example, ten subscribers, the use of a corresponding number of alternating currents of different frequencies or different code signal combinations, respectively. The subscribers of one group may be called over one line conductor and those of the other group over the other line conductor.

The object of the invention is to use as few control relays as possible for the various control operations including setting of the connector first in one and then the other direction, setting the ring control switch by impulses, and switching the ringing current from one to the other line conductor to effect calling of a subscriber in one or the other group.

The invention provides a control relay cooperating in its deenergized and energized condition with switch contacts and with another relay which energizes upon receipt of impulse series, for setting the connector in its two directions of motion, such control relay thereupon closing the circuit for the drive magnet of the ring control switch and effecting connection of the ringing current to the line conductor over which a line found to be idle is to be called in accordance with the setting of the ring control switch.

The foregoing and other objects and features will appear from the description which will be rendered below with reference to the accompanying drawing showing in schematic circuit representation an example of the invention. The drawing shows only the switching means and circuits required for an understanding of the invention.

The connector used is assumed to be a switch of the vertical-rotary type and the ring control switch is assumed to be a switch of the rotary type.

The invention will be described by tracing a call; some of the contact symbols will be briefly explained before doing so.

Contacts 2k, 28k, 31k are vertical off-normal contacts shown in normal position of the connector. These contacts are placed in alternate position when the connector is vertically off-normal.

Contacts 25w, 32w are rotary off-normal contacts which are actuated when the connector executes its first rotary step.

Contacts 3kr, 36kr, 40kr, 74kr are off-normal con-

2

tacts of the ring control switch which are actuated when the ring control switch leaves its normal position.

Referring now to the drawing, negative potential is connected to the private conductor 6 of an idle connector 5 by way of contacts 1b, 2k, 3kr, resistor 4 and contact 5c. After seizure of the connector by a group selector and after switching through of the line conductors 8 and 10, line relay A will energize in the loop circuit, one winding I of such line relay being connected to line conductor 8 over contact 7b and its other winding II being connected to conductor 10 over contact 9b. Contact 11a is opened and 12a is closed upon actuation of relay A, causing energization of relay C in a circuit

15 (1) +, C, 12a, resistor 13, —

Contact 5c is opened and contact 14c is closed responsive to actuation of relay C, placing positive potential on the private conductor 6 to mark it as being busy. Contact 15c is opened and contact 16c closed to close a circuit for relay V which however remains at normal, its winding being short-circuited by contact 12a.

Relay A deenergizes impulsewise in step with the impulses of the impulse series received from the calling party for the vertical setting of the connector, and relay 25 V is operatively connected in a circuit

20 (2) +, 11a, 17g, 16c, V, resistor 13, —

The vertical stepping magnet H is now stepped in a circuit

25 (3) +, 18p, 19g, 20a, 21u, 22w, H, —

Relays V and C remain energized during the receipt of the corresponding impulse series. Upon conclusion of the such impulse series, relay V deenergizes due to 35 the shunt over contact 12a which persists for an interval. Relay U is now energized in a circuit

30 (4) +, 23c, 24g, 25w, 26v, winding I of U, 27p, 28k, 1b, —

40 Upon energizing, relay U opens its contact 21u and closes contact 29u. The next impulse series does not affect the vertical magnet H but the rotary stepping magnet D. Closure of the contacts 30u prepares further control operations, among others, contacts 25w and 26v are bridged. Relay V energizes again upon receipt of the second impulse series which is effective for actuating the rotary magnet of the connector. The rotary stepping magnet D is actuated in a circuit

45 (5) +, 18p, 19g, 20a, 29u, 31k, D, —

Contact 33v being closed, relay RR will energize over its winding I in a circuit

50 (6) +, 23c, 24g, 32w, 33v, IRR, 27p, 28k, 1b, —

55 Incident to the first rotary step of the connector, the rotary off-normal contact 25w will open and contact 32w will close.

60 Of the contacts actuated by relay RR, the closure of contacts 35rr is of immediate interest. Winding II of relay U, which is in opposition to the winding I, as indicated by the numerals 1, 2, cannot become effective during the receipt of the impulses because it is short-circuited in a circuit

65 (7) IIU(1), 36kr, 35rr, 33v, GR6, IIU(2)

70 The short-circuit (circuit 7) is interrupted upon conclusion of the impulse series and restoration of relay V and opening of contacts 33v. The winding IIU is connected in the circuit "6," such winding being in series with winding IRR. Relay U deenergizes and restores its contacts to the illustrated position. Relay RR also de-

3

energizes, because after opening of contact 30u there is connected in its circuit the rectified GR6. The rotary stepping magnet Drw of the ring control switch RW is now subject to control by contact 20a, due to closure of contact 21u, rotary off-normal contact 37w being closed. The next (third) impulse series actuates the rotary magnet Drw. The rotary stepping magnet D of the connector cannot be affected because contact 29u is open. Relay V operates again upon receipt of the corresponding impulse series and the ring control switch RW is set to the position in which the code signal combination designating the selected subscriber is connected by way of the wiper 38. Instead of different code signal combinations, there may be used alternating ringing current of different frequencies. The wiper 38 of the ring control switch would in such case not lie on contact 39eII but on contact 40rr, while positive potential would be connected in certain time sequence for the energization of the ringing relay RR. The illustrated arrangement assuming different code signal combinations will now be described.

After the first step of the ring control switch, contacts kr are actuated, contact 36kr opening and contact 40kr closing. Relay RR energizes in the circuit "6" responsive to energization of relay V and closes its contact 35rr. Relay G cannot energize so long as contact 33v is closed because its winding is short-circuited. Upon conclusion of the impulse series and deenergization of relay V as well as opening of contact 33v, the winding IG is placed in series with winding IRR and relay G energizes in a circuit

(8) +, 23c, 24g, 32w, IG, 40kr,
35rr, IRR, 27p, 28k, 1b, —

Relay G closes for itself a holding circuit

(9) +, 23e, 42g, IIG, 43b, —

Contact 24g opens the circuit "8." Opening of contacts 17g and closing of contacts 44g causes switching over of relay V and secures subsequently upon release of the connection in cooperation with the rotary stepping magnets D and Drw, the release of the connector and the ring control switch.

At contact 42g is closed the test circuit

(10) +, 23c, 42g, GR1, IP, 45a, 46, T, —

Relay P energizes if the called line is idle. Closure of contacts 47p places the busy potential from contact 48c on the wiper 46. The holding winding IIP is at the same time connected. Contacts 18p and 27p are opened. The line conductors are switched through at contacts 49p and 50p. Closure of contact 51p prepares for the transmission of ringing current.

In order to avoid in the case of 10 subscribers on a party line the use of 10 ringing current sources with 10 different frequencies of 10 different code signal combinations, the subscribers are subdivided into two groups. The ringing of each subscriber Tn1 to Tn5 is effected over line conductor 52 and the ringing of each subscriber Tn6 to Tn10 over line conductor 53. Relay U determines to which line conductor the code signal combination is to be connected, relay U, as will be remembered, also controlling in its different switching positions the actuation of the vertical magnet H and of the rotary magnet D of the connector and also of the rotary magnet of the ring control switch RW. Relay U is deenergized during the setting of the ring control switch. When the ring control switch is set in one of the switching positions 1-5, the code signal applying will be connected to the line conductor 52. Setting of the ring control switch in one of the switching positions 6-10 will cause connection of the code signal to line conductor 53.

It shall be assumed first that the ring control switch is in one of the switching positions 1-5. The wiper 55 is in such case in engagement with one of the unconnected contacts.

4

Relay E will be energized upon closure of the contact 47p in a circuit

(11) +, 48c, 47p, IE(I), —

Relay E is operable in stages. Current flow through its winding I (right hand end-center of drawing) causes operation of relay E in its first stage as indicated by (I) following the letter E. Only contact 57eI (left hand bottom of drawing) will be closed in this first stage. In order to fully transmit the code signal allotted to the selected called subscriber, the ringing relay must be placed under control of the ringing device prior to the start of a code series. This is effected by a current impulse released by the ringing device, for example, by a cam controlled contact Na, at the end of each code series. This current impulse effects operation of the relay E to assume its second stage position, in a circuit

(12) +, Na, 57eI, IIE(II), GR3, 58g, 51p, 28k, 1b, —

Upon closure of contact 39eII, ringing relay RR will be energized over its winding II in accordance with the code signal series of the called subscriber. Relay RR opens its contact 60rr and connects the proper ringing current source at its contact 40rr. Ringing current flows over line conductor 52 and back over line conductor 53 to ground by way of contacts 63u and 61b, the latter contact short-circuiting winding II of relay B and preventing actuation thereof.

If the ringing control switch is set by corresponding impulse series to one of the positions 6-10, the wiper 55 will be in engagement with one of the interconnected contacts and, responsive to energization of relay P, relay U will be actuated in addition to relay E, in a circuit

(13) +, 48c, 47p, 55, IIIU, —

Upon actuating, relay U opens its contacts 62u, 63u and closes its contacts 64u, 65u, thereby switching the contacts 60rr/40rr from the line conductor 52 to line conductor 53.

Relay B energizes over the called subscriber's loop-circuit if the called party answers during a ringing pause. Relay B opens its contact 61b, removing the shunt across its winding II, extends the line conductors by closing contacts 66b and 67b, and closes its contacts 68b and 69b disposed respectively in parallel to contacts 23c and 48c. At contact 43b, relay B interrupts the circuit for the holding winding II of relay G. Opening of contact 1b and subsequently of contact 58g prevents renewed operation of relay RR.

The release of the connector and the ringing control switch is effected responsive to replacement of the receivers at both subscriber stations. Assuming that the calling subscriber hangs up first, relay A will restore, and thereafter C, because its winding will be shunted by contact 11a. Relay V will briefly energize which is, however, without consequence. At contact 70c, a circuit will be prepared for relay S. When the called party hangs up, relay B will restore, thereby freeing the corresponding party line, positive busy potential being now disconnected from the wiper 46 at contacts 48c and 69b. Relays P, E, and U which is actuated only in connection with certain calls, restore. Relay S energizes in a circuit

(14) +, 70c, 71wu, S, 34rr, IRR, 27p, 28k, 1b, —

65 The contact 71wu is closed so long as wipers of the switch are in engagement with bank contacts; it opens when the wipers leave the bank contacts. Relay RR cannot energize in the circuit "14" due to the high resistance of the winding of relay S. Upon closure of contact 72s, the rotary stepping magnet D of the connector and the drive magnet Drw of the rotary switch will be connected in a circuit

(15) +, 18p, 72s, 73v, $\frac{31k}{74kr}$, $\frac{D}{GR5, Drw}$, —

Relay V is now connected over contacts 75 and 76drw, in a circuit

(16) +, $\frac{75d}{76drw}$, 15c, V, 13, -

The circuit "15" is interrupted at contact 73v and both magnets D and Drw restore. Circuit "16" is opened. The alternate closing and opening of the circuits "15" and "16" persists until both switches are in home position and off-normal contacts 74kr and 31k are accordingly open, thus preventing further operation. The idle potential is reconnected to the incoming private conductor 6 at off-normal contacts 3kr and 2k.

Changes may be made within the scope and spirit of the appended claims.

I claim:

1. In a telephone system having party lines and, a connector switch comprising wipers for selectively extending calls from calling stations to subscribers on said party lines, said connector switch having two stepping magnets which are responsive to impulse series received from a calling station for setting said wipers in two directions of motion in extending a call to a party line subscriber and having a ring control switch comprising a drive magnet individual thereto and having circuit means for setting said ring control switch in accordance with an impulse series received and denoting a desired party line subscriber and further having a relay which is operatively actuated during the receipt of impulse series; a control relay, circuit means including off-normal contacts of said connector and contacts controlled by said first named

relay for governing the operation of said control relay, said control relay having the triple function of governing, first, the operation of circuit means for operating said two stepping magnets of said connector switch, second, of governing the operation of said ring control switch, and, third, of governing circuit means for connecting ringing current to one or the other line conductor of the corresponding party line.

2. A circuit arrangement according to claim 1, wherein 10 said control relay comprises two opposing windings, circuit means for energizing said relay over one of said windings to effect control of the setting operations of said two drive magnets, and circuit means, controlled by said first named relay upon deenergization thereof responsive to setting said connector switch, for energizing said other opposing winding to restore said control relay to normal.

3. A circuit arrangement according to claim 2, comprising a third winding for said control relay, circuit means controlled by said ring control switch in predetermined positions thereof for energizing said control relay over said third winding, and circuit means thereupon controlled by said control relay for switching ringing current from one to the other line conductor.
